(57) **CLAIM**

The ornamental design for a electronic bracelet for access control, as shown and described.

DESCRIPTION

FIG. 1 is a perspective view of an electronic bracelet for access control according showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of the electronic bracelet for access control;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

In FIG. 7, the broken lines defining the semi-circular elements on the underside of the band depict environmental subject matter that forms no part of the claimed design.
